UNITED STATES PATENT OFFICE.

WILLIAM P. BETTENDORF, OF BETTENDORF, IOWA; J. W. BETTENDORF ADMINISTRATOR OF SAID WILLIAM P. BETTENDORF, DECEASED.

CUSHIONING DEVICE FOR INDEPENDENTLY-MOVABLE CAR-BODIES.

1,084,690.

Specification of Letters Patent. Patented Jan. 20, 1914.

Application filed May 23, 1910. Serial No. 562,923.

To all whom it may concern:

Be it known that I, WILLIAM P. BETTENDORF, a citizen of the United States, residing at Bettendorf, in the county of Scott 5 and State of Iowa, have invented new and useful Improvements in Cushioning Devices for Independently-Movable Car-Bodies, of which the following is a full, clear, and exact description.

10 The object of my invention is to provide means for cushioning and automatically returning to their original positions the bodies of railway cars having a slight longitudinal movement independent of the underframe.

15 A further object of my invention is to combine means for utilizing the weight of the car-body and the cushioning elements in one mechanical movement.

20 Yet another object is to enable these functions to be accomplished without resorting to any unusual construction of the underframe elements, excepting possibly the ends of the bolsters. This I accomplish by the means hereinafter fully described and as 25 particularly pointed out in the claims.

25 In the drawings: Figure 1 is a side view of a fragmentary portion of the tank car taken in the transverse plane of the bolsters, and showing the end of the body-bolster in 30 vertical section. Fig. 2 is an end view of one-half portion of the tank car embodying my improvement. Fig. 3 is a plan view of the saddle for said tank car and adjacent portions of other underframe members.

35 Referring to the drawings, A represents the tank of a tank car, although it will be apparent from the following description of my invention that, with the exception of slight changes, they could be applied to a 40 car-body having a flat bottom.

B represents a suitable saddle-plate in which said tank is securely seated by riveting or otherwise. This saddle-plate extends from one side of the car to the other and is 45 nearly as long as the body-bolster C, and at its ends it is provided with webs or flanges a that extend at a downward angle therefrom a short distance, and converge toward and merge into suitable bosses b, b, between 50 which latter their lower portions are recessed to provide room for two segmental shaped rockers D. Each of these rockers, preferably, consists of two parallel segmental webs the curved edges of which are connected by a suitable tread, which latter is

provided at its center of length with an elongated opening D'. An inverted large eye-bolt E is located so that the eye thereof will come between the segmental webs of the rockers, and be journaled on the same pivotal bolt c, the ends of which latter are secured in the ends of bosses b, b. The curved treads of rockers D are provided with transverse teeth that engage and are supported upon the transverse teeth d in the bottom of transverse channels, e, made in the body-bolsters C near the ends thereof, and the curved treads of these rockers are struck from a center, the radius of which is greater than the radius from the center of the bolt c to the center of length of said curved tread. As a consequence of this construction when the tank or car-body A moves longitudinally in either direction, the full movement of rockers D will raise the tank a suitable distance, and the force that causes the tank to move longitudinally independent of the bolsters, will exhaust itself in lifting the tank. 70

75 Gravity which causes the automatic return of the car-body to its normal position 80 is assisted by means of coiled springs F, one of which is employed in connection with each rocker. There is an elongated opening J in the center of length of each channel e, and the shaft of the inverted eye-bolt E extends down through opening D' in the tread of the rocker and down through said opening J, into a cylindrical chamber in the end of the bolster below said channel, and is there surrounded by said coiled spring, which is retained thereon by means of a suitable washer G secured on the lower end of the bolt by nut h. When the rockers move in either longitudinal direction these springs, F, are compressed between said 85 washers and the underside of the bottom of the channel, and resist said movement and their subsequent expansion assists in restoring the rocker and car-body to their positions of rest. This construction also effectively prevents excessive longitudinal movement of the body or tank independent of the underframe owing to the fact that in the event of the springs F being entirely compressed the eye-bolt E will act as a tie and 90 retain the tank on the underframe. 100

105 What I claim as new is:—

110 1. The combination with an underframe, a suitable car-body capable of a slight longitudinal movement independent of said

underframe, of rockers that raise said car-body during said longitudinal movement and the pivots of which are connected to said car-body and rest upon and engage said underframe, and means operatively connected to said car-body for limiting the longitudinal movement thereof.

2. The combination with an underframe, a suitable car-body capable of a slight longitudinal movement independent of said underframe, of rockers the pivots of which are connected to said car-body and support the same, which rockers have their treads eccentric to their pivots and rest upon and engage said underframe, and means operatively connected to said car-body for limiting the longitudinal movement thereof.

3. The combination with an underframe, a suitable car-body capable of a slight longitudinal movement independent of said underframe, of automatically returnable rockers that raise said car-body during said longitudinal movement the pivots of which are connected to said car-body and rest upon and engage said underframe, and means operatively connected to said car-body for limiting the longitudinal movement thereof.

4. The combination with an underframe, a suitable car-body capable of a slight longitudinal movement independent of said underframe, of automatically returnable rockers the pivots of which are connected to said car-body and support the same, which rockers have their treads eccentric to their pivots and rest upon and engage said underframe, and means operatively connected to said car-body for limiting the longitudinal movement thereof.

5. The combination with an underframe, a suitable car-body capable of a slight longitudinal movement independent of said underframe, of rockers that raise said car-body during said longitudinal movement the axes of which are pivotally connected to said body, distinct means operatively connected to said car-body including springs for returning said rockers to their original positions which latter rest upon and engage said underframe, and a device for limiting the longitudinal movement thereof.

6. The combination with an underframe, a suitable car-body capable of a slight longitudinal movement independent of said underframe, of rockers the axes of which are pivotally connected to said car-body and support the same, the treads of said rockers being eccentric to their pivots, springs for returning said rockers to their original positions which latter rest upon and engage said underframe, and a device engaged by said spring for limiting the longitudinal movement of the car-body.

7. The combination with an underframe, a suitable car-body capable of a slight lon-

gitudinal movement independent of said underframe, and body-bolsters therefor, of rockers pivotally connected to and supporting said car-body and adapted to rock on the ends of said bolsters, and means operatively connected to said car-body for limiting the longitudinal movement thereof.

8. The combination with an underframe, a suitable car-body capable of a slight longitudinal movement independent of said underframe, and body-bolsters therefor having transverse channels in their ends, of rockers pivotally connected to and supporting said car-body and adapted to rock in the said channels of said body-bolsters, and means operatively connected to said car-body for limiting the longitudinal movement thereof.

9. The combination with an underframe, a suitable car-body capable of a slight longitudinal movement independent of said underframe, and body-bolsters therefor that have a transverse rack on each end, of rockers pivotally connected to and supporting said car-body and having their curved treads provided with teeth that engage said rack, and means operatively connected to said car-body for limiting the longitudinal movement thereof.

10. The combination with an underframe, a suitable car-body capable of a slight longitudinal movement independent of said underframe, of body-bolsters therefor that have a transverse channel in each end, the bottom of which is provided with a transverse series of cogs, rockers pivotally connected to and supporting said car-body and having their curved treads provided with cogs that engage those in the bottoms of said channels, and means operatively connected to said car-body for limiting the longitudinal movement thereof.

11. The combination with an underframe, a suitable car-body capable of a slight longitudinal movement independent of said underframe, of body-bolsters therefor, automatically returnable rockers pivotally connected to and supporting said car-body and adapted to rock on the ends of said bolsters, and means operatively connected to said car-body for limiting the longitudinal movement thereof.

12. The combination with an underframe, a suitable car-body capable of a slight longitudinal movement independent of said underframe, of body-bolsters therefor, having transverse channels in their ends, automatically returnable rockers pivotally connected to and supporting said car-body and adapted to rock in the said channels of the bolster, and means operatively connected to said car-body for limiting the longitudinal movement thereof.

13. The combination with an underframe

a suitable car-body capable of a slight longitudinal movement independent of said underframe, of body-bolsters, rockers pivotally connected to and supporting the said car-body and adapted to rock on the ends of said bolsters, springs for retaining said rockers in normal position, and means operatively connected to said car-body for limiting the longitudinal movement thereof.

10 14. The combination with a suitable car-body capable of a slight longitudinal movement independent of its underframe, of body-bolsters, rockers pivotally connected to and supporting the said car-body and adapted to rock on the ends of said bolsters, eye-bolts whose upper ends engage the pivotal members of said rockers and whose lower ends extend into the ends of said bolsters, and springs surrounding the retained ends of said bolts.

15 15. The combination with a suitable car-body capable of a slight longitudinal movement independent of its underframe, of body-bolsters, rockers, the curved treads of which are eccentric to the pivotal centers of said rockers, pivotally connected to and supporting the said car-body and adapted to rock on the ends of said bolsters, eye-bolts whose upper ends engage the pivotal members of said rockers and whose lower ends extend into the ends of said bolsters, and springs surrounding the retained ends of said bolts.

20 16. The combination with a suitable car-body capable of a slight longitudinal movement independent of its underframe, of body-bolsters having transverse channels in their ends, the bottoms of which are provided with cogs, and rockers pivotally con-

nected to and supporting said car-body, the curved treads of which are eccentric to their pivots and are provided with cogs that engage the cogs in said channels, eye-bolts the upper ends of which engage the pivots of said rockers and the lower ends of which extend through suitable openings in the bottom of said channels, and springs surrounding said eye-bolts below said openings.

25 17. The combination with an underframe, a superposed car-body capable of a slight longitudinal movement independent of said underframe, and a transverse member to which said car-body is secured, of rockers that are pivotally secured to said transverse-member.

30 18. The combination with an underframe, a superposed car-body capable of a slight longitudinal movement independent of said underframe, and a transverse member connected to said car-body, and having pivotal devices at each end thereof, of rockers that are pivoted to the pivotal devices of said transverse-member.

35 19. In a car the combination with an underframe, a superposed tank capable of a slight longitudinal movement independent of said underframe, and a transverse saddle member in which said tank is seated having pivotal devices depending from the ends thereof, of rockers that are pivotally connected to the depending pivotal devices of said transverse-member.

In witness whereof I have hereunto set my hand this 19th day of May, 1910.

WILLIAM P. BETTENDORF.
